UNITED STATES PATENT OFFICE.

HENRY L. PITMAN, OF WESTFIELD, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed April 18, 1923. Serial No. 632,836.

The invention relates to typewriting machines in connection with which a motor is employed for driving the carriage. More particularly, the invention is concerned with 5 the use of an electric motor for automatically returning the carriage, and with make-and-break connections for the motor-drive and motor-circuit. The invention has also special reference to the motor and transmission-gear supports and assemblages.

Ordinarily a pinion, in mesh with a rack on the carriage, is driven through make-and-break connections from the motor. The motor and certain of the transmission-gearing are usually located behind the main frame of the machine, and the transmission-gearing, so located, usually comprises a clutch-member for co-operation with a clutch-member on the shaft of the pinion 20 which meshes with the rack; so that, by rearward and forward movement of the latter clutch-member on its shaft, the same may be made to engage and disengage the clutch-member on the rear transmission-gearing to make and break the connections from the motor to the carriage. A machine of this class, however, commonly has a tabulator-stop frame along which tabulator-stops are adjustable to selected column-positions; and this frame normally lies between the transmission-gearing, above referred to, and the rack on the carriage, driven by such gearing; with the result that heretofore the continuity of the tabulator-stop frame has 30 been broken to permit movement across the same of the clutch-member above mentioned, and movement of a tabulator-stop from one to the other end of the stop-frame has thereby been rendered impossible.

40 A feature of the present invention is a novel and simple construction and mounting of the shiftable clutch-device, such that mutilation of the tabulator-stop frame, to allow for the shift, is unnecessary, and such that no tabulator-stop is prevented from movement to any position on the stop-frame.

Heretofore both the motor and the transmission-gearing (the latter in a casing containing a lubricant) have been mounted on the typewriting machine; the motor shaft being suitably aligned with, but disconectible from, one of the shafts of the transmission-gearing. It may not always be desirable thus to encumber the machine with

the motor and special attachments therefor. 55 With the motor clear of the machine, the latter is more easily carried, different machines and motors are rendered more readily interchangeable for repairs, and less departure from the standard manual carriage- 60 return machine is involved than where the motor is secured directly to the machine. It is not always important that the automatic carriage-return be employed, and at such times the motor, if on the machine, is 65 only an unnecessary adjunct.

An object of the present invention is the provision of means whereby the motor may be supported independently of the machine; and the motor, the transmission gear-casing, 70 motor circuit-connection box and other elements be handled as independent units, readily assembled and individually replaced, in their combination with each other and with the elements in the machine which they 75 control or are controlled by.

A feature of the invention is a mounting for the motor such that adjustment of the same for effecting alignment of the motor-shaft with the element which it is to drive, 80 may be readily had. In the preferred form of the invention, hereinafter described, a casing fixed to the machine frame contains transmission-gearing with which the motor-shaft is aligned by angular adjustment of 85 the motor around a bolt which supports the same from a table behind the machine. This adjustability of the motor may also be utilized to permit the motor to be moved back as a unit with the gear-casing in disconnecting the gears therein from the carriage and in disconnecting the gear-casing from the machine frame; whereupon the gear-casing may be moved laterally with respect to the motor to disconnect the gears 90 in the casing from the motor-shaft. The motor is also removable alone, whenever desired, without disturbing the gear casing by disconnecting the motor from its support, whereupon the motor may be moved laterally 95 100 with respect to the gear casing to disconnect the motor-shaft from the gears of the gear casing. For assembling, these movements may be made in the reverse direction. The tilting of the motor about its pivotal support, or the removal of the motor or transmission gear, or both, from the machine, affords unrestricted access to the

escapement and other parts at the rear of the machine for repair, adjustment or other purposes.

Where the motor drive is for a machine of the so-called continuous-billing class, the base-plate which supports the carbon-carrier table, over which the web is led to the platen, may conveniently be employed as a support for the motor independent of and behind the main frame of the machine. The carbon-carrier table also in such cases co-operates with the brackets upon which it is supported above the base-plate to constitute a substantial protective enclosure for the motor and transmission gear casing.

Other features and advantages will hereinafter appear.

In the accompanying drawings,

Figure 1 is a view, in side elevation, of the machine and associated mechanisms, taken on the line 1—1 of Figure 2.

Figure 2 is a view, in rear elevation, of the machine and associated mechanisms.

Figure 3 is a view, in side elevation, showing the connections to the carriage-escapement mechanism and tabulator-stop frame.

Figure 4 is a view, in rear elevation, of the transmission-gear-case, partly cross-sectional.

Figure 5 is a view, in cross-section, on the line 5—5 of Figure 4.

Figure 6 is a view, in cross-section, on the line 6—6 of Figure 4 with certain of the parts removed.

Platen 10 is rotatably mounted in a carriage 11, which is supported on a front rail 12 and a rear rail 13 for movement in letter-feed and return directions on the main frame of the machine. The movement of the platen-carriage in letter-feed direction is effected by a strap 14, connected at one end to the carriage and at the other end to the usual spring-drum 15; the movement being controlled by suitable escapement mechanism

comprising a rack 16 connected to the carriage to move therewith, a pinion 17 meshing with the rack and having a one-way connection, through a pawl, not shown, with an escapement-wheel 19, and fixed and loose dogs

20 and 21, respectively, co-operating with the escapement-wheel and operated by a universal bar 22 in the path of the type-bars 23. The rack 16 is supported on arms 24, pivoted at 25 to the sides of the carriage. These arms are adapted to be swung up to lift the rack out of engagement with the pinion 17, and thereby to release the carriage from the control of the escapement mechanism so that the carriage may be thrown by the spring-

drum from one to another column or tabulating position determined by stops. When, by reason of gravity drop, the rack 16 is in engagement with the pinion 17, it rides upon and is supported by means of a roller 26, carried on a lever 27 pivoted at 28 to the es-

capement-frame member 29. A stop-screw 30, threaded into an ear 31 on the lever 27, by abutment with a shoulder 32 on the frame-member 29, determines the normal position of the lever and rack-supporting roller 26. When the lever 27 is swung around its pivot 28, to lift the roller 26, the rack 16 is disengaged, as above mentioned, from the pinion 17.

The lever 27 is conveniently operated, to release the rack, by means of a finger 33, which is secured to a cross-piece 34 of a tabulator-stop frame 35; so that, when the tabulator-stop frame is swung in counterclockwise direction, around a pivot 36, by means of a link 37, connected to the tabulator-key lever, not shown, the finger 33, by engagement with and depression of the tail-piece 38 of the lever 27, swings the latter in a direction to throw the rack up out of engagement with the pinion 17.

The link 37 is pivotally connected at 39 to a tabulator-stop frame shown as of the type found in the Underwood machine. Rigidly connected to the cross-bar 34 of this frame, at each end thereof, is an arm 40, the upper ends of which are connected by a bar 41. The face 42 of the bar 41 is graduated to present a letter-space scale; and a rack 43 is formed on the under side of this bar. Pivoted on, and slidably adjustable along, a rod 44, carried by the arms 40, are the tabulator-stops 45. There may be any desired number of these tabulator-stops. Three such stops are shown to the right of the center of Figure 2, and one to the left of the center of Figure 2; Figure 2 being a rear view of the machine. Each tabulator-stop is in the form of a blade, the upper edge 46 of which is adapted to co-operate with the teeth of the rack 43. By means of a finger-piece 47, unitary therewith, the stop may be rocked backward on the rod 44 to be disengaged from the rack 43; whereupon, also by means of the finger-piece 47, the stop may be slid along the rod 44 to its desired column or tabulating position indicated by registration of a pointer 48 on the stop with the graduations of the scale 42. Thereupon the stop is swung angularly forward to cause the blade 46 to enter between the teeth of the rack, and, by the latter, held against longitudinal movement on the rod 44. Suitable means, not shown, are provided for holding the stop against angular displacement from the rack 43.

With the several stops in selected position on the tabulator-frame, the latter may be swung, by means of the tabulator-key and link 37, from the Figure 3 position to a position in which the stops lie in the path of a fixed stop 50 on the carriage 11. If, at this time, the carriage is released to the action of the spring-drum, the fixed stop 50, after a predetermined throw of the carriage, will

strike the first stop to the left thereof and be arrested in a given column position. Upon release of the tabulator-key, the tabulator-stop frame, whether by the gravity action of the rack 16 acting through the lever 27, or by other means not shown, will return to Figure 3 position. By subsequent operations of the tabulator-key, the carriage is stepped progressively to the positions determined by the tabulator-stops.

On reaching the left-hand margin-stop, connections are set which cause the carriage to be automatically returned by means of a motor 51. By means shown in patent to F. A. Hart, No. 1,238,908, dated September 4, 1917 (see particularly Figure 6 thereof), the left-hand margin-stop may be set at any desired letter-scale position on a rack numbered as 52 in Figure 1 of the drawings of the present case, so that, when a dog or detent on the carriage reaches the left-hand margin-stop, such rack will be depressed to actuate a link 53 connected thereto. In the present case, this link 53 is shown as pivotally connected at 54 to the rack so as to have a downward thrust when the carriage reaches the margin-stop. The lower end of the link 53 is pivotally connected at 55 to the forward end of a rocker 56, pivoted at 57 on the main frame 58 of the machine. The rear end of the rocker underlies a pin 59 on a link 60. A spring 61, connected at one end to the link 60, and at its other end to the main frame 58, pulls downward and rearward upon the link. The link 60, near its forward end, is, however, recessed in its under edge at 62 to engage a comb-plate 63 and normally to be held by the latter against the action of the spring 61. When the link 53 is depressed to actuate the rocker 56, the latter, by engagement with the pin 59, lifts the link free of the comb-plate and releases the link to rearward movement by the spring 61. At its rear end the link connects with an arm 64 fast on a rock-shaft 65; so that rearward movement of the link 60 will cause rearward swing of an arm 66 also fast to the shaft 65. The arm 66 connects at 67 to a slide 68, and a spring 69 connects an ear 70 on the slide 68 and an ear 71 on a second slide 72, to cause rearward movement of the slide 72 upon sufficient tension of the spring 69 after release of the link 60. The slide 72 operates a switch, not shown, in a connection-box 73, to close the circuit of the motor 51. The wires from the connection-box to the motor are indicated at 74. The box 73 is secured by screws 75 to the frame-piece 58 of the machine.

The drive from the motor to the carriage is as follows. The motor-shaft 75 (see Figures 2 and 4) is loosely set into a sleeve 76 integral with a shaft 77, to which a worm 78 is made fast by means of a pin 79. The connection between the motor-shaft 75 and

the worm-shaft 77 is by means of a cross-pin 80 in the motor-shaft setting loosely into a cross cut or cuts 81 in the end of the sleeve 76. The looseness of the shaft 75 in the sleeve 76, and the looseness of the pin 80 in the cross-cut 81, is to assure a driving connection between the two shafts even though the alignment of the two may not be perfect. The worm-shaft 77 is journaled in a block 82 forming part of a gear-casing, supported, in a manner presently to be described, behind the typewriting machine. A chamber 83 in the casing-block 82 contains the worm 78 and also a bushing or bearing-piece 84 for the worm-shaft 77; the bearing-piece 84 being adjustable within the chamber 83 by means of a set-screw 85 (see Figures 4 and 5), threaded through the block 82 and bearing against the bearing-piece. The end 86 of the shaft 77 has its bearing in a countersink 87 forming an extension of the chamber 83. A ball 88 receives the end thrust of the shaft 77 and serves as a frictionless end-bearing for the latter. The shaft 77 and worm 78 are prevented from longitudinal displacement in the other direction by abutment of the worm with the end of the adjusted bearing-block 84.

The worm 78 meshes with a gear 89, keyed at 90 to a hub 91, journaled for rotation in the casing-block 82. The casing-block is countersunk at 92 to receive bushings 93 and 94, the inner peripheries of which are oppositely tapered to form one part of a runway for ball-bearings 95; the other part of the runway being provided by an exterior peripheral groove 96 in the hub 91. Screws 97, passing through the bushings 93 and 94 and into the block 82, demountably secure the hub 91 in place. The forward face of the hub 91 carries one member 98 of a clutch; the other member 99 of the clutch being secured by a set-screw 100 to a shaft 101, journaled at one end in the hub 91 concentric with the hub and with the gear 89.

The casing is adapted to hold oil for the bearings of the worm and gear therein contained, and, for this purpose, is closed by a plate 102. The plate 102 is set on shoulders 103 on the block 82, and is secured to the latter by screws 104. A finger-piece 105, secured to the plate 102, serves as a means for positioning and removing the same.

The shaft 101 is movable longitudinally of its axis to make and break the drive from the motor to the carriage by bringing together or disconnecting the clutch-members 99 and 98. The forward end of the shaft 101 (see Figures 1 and 2) has bearing in a bracket 106, offset from and secured by screws 107 to another bracket 108, which latter is, in turn, secured by screws 109 to one of the rear posts of the typewriting machine. The bracket 108 also serves as a sup-

port for the gear-casing-block 82. For this purpose, a pair of bolts or posts 110 are provided. These posts have reduced ends 111 to provide shoulders for setting the posts 110 against the rear face of the bracket 108; and these reduced ends are threaded into the bracket 108. As shown in Figure 6, the rear ends of the posts 110 are shouldered at 112 to be set against the rear face of the casing-block 82 and to provide reduced portions 113 set into countersinks 114 in the block 82. Headed screws 115 and 116 are passed through holes 117 and 118, respectively, in the gear casing or block 82 in the rear of the latter and thread into the ends of the posts 110. The holes 117 and 118 are enlarged in the form of countersinks to receive the screw heads and to provide shoulders 119 against which the heads may bear, so that, when the screws are tightened, the ends of the posts 110 will be drawn and held against their seats in the casing block 82.

When the clutch-members 99 and 98 are brought together by a rearward movement 25 of the shaft 101, the drive from the shaft 101 to the carriage is effected through a gear 120 which is fast to the shaft 101 and which meshes with a rack 121. The rack 121 is supported on guides 122 carried by brackets 30 123 on the carriage 11. The guides 122 are received in slots 124 formed in the rack, the slots being of sufficient length to permit limited movement of the rack relatively to the carriage. Headed screws 125, engaging the 35 rear face of the rack and attached to the guides 122, retain the rack in position on the guides. When movement of the rack by the motor is initiated, the rack moves relatively to the carriage until the guides 122 engage the ends of the slots 124 in the rack, 40 after which the rack and carriage move in unison. During the period when the rack is moving relatively to the carriage, the platen is automatically line-spaced. The 45 manual line-spacing mechanism may be that common to the Underwood standard typewriter, and comprises a slide 126, operable by a line-space lever, not shown, and carrying a pawl, not shown, for turning the 50 ratchet-wheel on the platen-shaft. To effect automatic line-spacing of the platen through the initial movement of the rack 121 relative to the carriage, connections are provided from the rack 121 to the slide 126. 55 These connections comprise a pin 127 depending from the slide 126 and loosely fitted in a fork in the end of an arm 128 fast to a vertical rock-shaft 129 suitably journaled in brackets 123 and 130 on the carriage. 60 Fast to the lower end of the shaft 129 is an arm 131 loosely set in a niche 132 in the lower edge of the rack 121. When, therefore, the rack receives its initial movement above mentioned, it rocks the arm 131, shaft 129 and arm 128 to throw the pawl-carrying 65

line-space slide 126. At the time the guides 122 have reached the end of the slots 124, line-spacing has been effected, and thereafter on further movement of the rack 121 by the gear 120 return movement of the carriage is effected. 70

The clutch-members 98 and 99 are normally separated, as shown in Figure 5, but are brought together by the same movement of the link 60 which closes the motor-circuit. 75 For this purpose, the shaft 65 has a third arm 133 fast thereto, connecting with a link 134, in turn connected to an arm 135 fast to a rock-shaft 136 journaled in the bracket 106. Also fast to the shaft 136 is an arm 137 80 terminating in a ball 138 which is set between flanges 139 and 140 on a sleeve 141 fast to the gear-shaft 101. When, therefore, the link 60 is thrown rearward by the spring 61 to rock the shaft 65, the link 134 85 is drawn forward and the arm 137 swung rearward with the shaft 101 to throw the clutch-member 99 to the clutch-member 98. This operation may take place before the 90 spring connection between the slides 68 and 72 has operated to close the motor-circuit.

When the carriage reaches the right-hand margin stop, certain connections are operated to throw the shaft 101 forward to disconnect clutch-member 99 from clutch-member 98. These connections may consist, in part, of certain mechanism, shown in Figure 4 of the aforesaid patent to Hart, whereby a shaft therein numbered as 42 and numbered in Figure 1 of the present application 100 as 142 is partially rotated to swing forward an arm 143 fast thereto. The arm 143 connects with the forward end of a link 144, the rear end of which connects with another link 145 guided by means of a pin-and-slot connection 146 on the main frame. The link 145 connects with a third arm 147 on the shaft 136; so that, when the right-hand margin stop acts to draw forward the links 144 and 145, the shaft 136 will be turned to 105 cause the arm 137 thereon to draw forward the shaft 101 a distance sufficient to separate the clutch-members 99 and 98. 110

It will be noted that the gear 120, which drives the rack 121 for automatic return of the carriage, is of a width sufficient to permit it to remain in mesh with the rack 121 whatever the shifted position of the shaft 101. It will also be noted (see Figure 1) that the required rearward movement of the 115 shaft 101, in connecting the clutch-members, is insufficient to cause the gear 120 to strike or to be obstructed by the cross-piece 34 of the tabulator-stop frame. The lower edge 120 of the cross-piece 34 may, however, be 125 slightly cut away, as is indicated at 148 in Figure 1, to accommodate the shaft 101 by reason of the fact that the contiguous planes of the shaft 101 and cross-piece 34 intersect and overlap each other. The cut 148 re- 130

duces the cross-sectional area of the cross-piece 34, but does not, however, interfere with the continuity of the cross-piece 34 and rod 44 of the tabulator-stop frame; and, 5 since no break in that continuity is required to permit of movement of the gear 120, the tabulator-stops 45 may at will be moved along the tabulator-stop frame from one to the other side of the shaft 101.

10 The invention is shown as applied to a typewriting machine of the so-called continuous billing class. In such machines, a continuous form-web is ordinarily fed from the rear over a table 149 secured as at 150 15 to the carriage of the typewriter to move therewith in letter feed and return directions, and a bracket 151 is provided at each side of the machine to support a rear rail, not shown, on which the rear of the table 20 149 may rest and ride with the typewriter carriage above the motor 51 and gear casing block 82. In addition to its other purposes the table 149 co-operates with the brackets 151 in substantially enclosing the 25 motor and gear casing at the rear of the machine to prevent interference with the work. In Figure 1, one of the brackets 151 is shown as carried by a base-plate or table 152, which is extended forward as a support 30 also for the typewriting machine. The table 152 may be a rectangular channel bar skeleton having side channel bars 153, front and rear channel bar cross-pieces, not shown, and an intermediate channel cross-bar piece 35 154. Feet 155 of the typewriter may pass through openings in the channel-bar structure. The intermediate channel bar cross-piece 154 may be turned rearward, intermediate the sides of the table 152 to form a 40 U, the rearward cross reach of which U is indicated in cross-section at 156 in Figure 1. This rear reach 156 is employed as a support for the motor, so that the machine itself may be relieved of the weight of the 45 motor and of all devices for connecting the motor thereto, and so that the motor and machine may be handled independently of each other. For supporting the motor on the cross-piece 156, posts 157 are provided. 50 These posts have reduced lower ends 158, which are threaded through the cross-piece 156, and have reduced upper ends 159, which provide shoulders 160 to support a bracket 161, and onto which nuts 162 are threaded 55 to hold the bracket 161 on its seat. Suitable spacing means are also preferably provided for adjusting the height of the motor-shaft 75 relatively to the worm-gear transmission-sleeve 76. For this purpose one or 60 more shims or washers 175 may be interposed between the lower ends of the posts 157 and the upper surface of the cross-piece 156, the reduced diameter threaded portions 158 passing through the washers 175 and 65 being screwed down onto the cross-piece

156. The bracket 161 has integral therewith a block 163 through which a bolt 164 is passed.

The motor-casing has a pair of depending ears 65, one at each side thereof, and which 70 overlie the ends of the block 163. The ears 165 are perforated to permit passage therethrough of the bolt 164, and the end of the bolt is threaded to receive nuts 166 which are adapted to be turned in against the ears 75 165. When the nuts 166 are loosened, the motor-casing may be swung radially about the axis of the pivotal support provided by the bolt 164. Upon tightening the nuts 166, the motor will be held upright in its Figure 80 1 position.

The angular adjustment of the motor on the bolt or axis 164 provides for movement forward and rearward of the motor-shaft 75 for alignment of the same with the 85 worm-shaft 77. This angular movement of the motor is also for the purpose of assembling and disassembling the parts. To remove the gear-casing 82, for instance, the screws 115 and 116, which hold the motor 90 against angular displacement, may be loosened and the motor together with the gear-case swung back until the shaft 101 is clear of the gear-case. Thereupon the gear-case may be drawn sidewise to clear the worm-shaft 77 95 of the motor-drive shaft 75. The gear-case is then free of the machine, and the motor may then be removed by withdrawing the bolt 164. The motor 51 may be removed without disturbing the transmission gear casing 82 by removing the bolt 164 and moving the motor away from the gear casing 82 to disconnect the motor-drive shaft 75 from the worm-shaft 77. For assembling the parts, 100 these operations are performed in reverse 105 order. The removal of the motor 51 or gear casing 82, or both, from the machine, or tilting of the motor 51 upon its pivotal support, as above described, permits ready access to be had to the escapement and other 110 parts at the rear of the machine for purposes of adjustment, repair or otherwise. The connection-box 73 is shown as provided with terminal clips 167 for receiving the socket or connection-piece of the line (not shown) 115 through which the power for driving the motor is supplied.

For effecting automatic return of the carriage at any time, a key 168 is provided. This key is mounted upon one arm 169 of 120 a bell-crank lever, the other arm 170 of which terminates in a nose under a block 171, pivoted at 172, on the shift-link 60. A pin 173 prevents clockwise (Figure 1) movement of the block 171 on its pivot; so that, 125 when the arm 170 swings forward against the block, the link 60 is lifted and freed from the comb-plate to the action of the spring 61. A coil-spring 174 returns the bell-crank and key 168 to normal position. In such return 130

movement, the arm 170 rocks the block 171 in the direction of the driving shaft and counterclockwise on its pivot 172, and is thus enabled itself to return to normal position.

Variations may be resorted to within the scope of the invention, and portions of the improvements may be used without others.

Having thus described my invention, I claim:

1. The combination with a typewriting machine having a platen-carriage, movable in letter-feed and return directions, of carriage feeding mechanism including escapement devices, a motor, a support for the machine, an extension of said support behind the machine, a bracket above said supporting extension, said motor being supported on said bracket directly at the rear of the escapement devices, driving connections from the motor to the carriage including a shaft, and a horizontal pivotal connection between said motor and said bracket for rendering the motor displaceable downwardly, to give free access to the escapement devices, said motor being disconnectible from said driving shaft.
2. The combination with a typewriting machine, having a platen-carriage, movable in letter-feed and return directions, of a motor, a support for the machine, an extension of the support behind the machine, posts on the extension, a bracket on the posts for supporting the motor, and driving connections from the motor to the carriage.
3. The combination with a typewriting machine, having a platen-carriage, movable in letter-feed and return directions, of a motor, a common support for the typewriting machine and the motor, means for demountably securing the motor on its support independently of the machine, comprising a bracket on the support, bosses on the motor, and a removable bolt passing through the bracket and the bosses, and driving connections from the motor to the carriage.

4. The combination with a typewriting machine, having a platen-carriage, movable in letter-feed and return directions, of a motor, a common support for the typewriting machine and the motor, means for demountably securing the motor on its support, independently of the machine, comprising a bracket on the support, bosses on the motor, a removable bolt passing through the bracket and the bosses, and a nut on the bolt adapted to be tightened and loosened with respect to the adjacent boss, to provide for angular adjustment of the motor around the axis of the bolt, and driving connections from the motor to the carriage.

5. The combination with a typewriting machine, having a platen-carriage, movable in letter-feed and return directions, a rack on the carriage, and a pinion meshing with the rack, of a motor having a drive-shaft, a transmission-shaft connected to the pinion, and pivotal means for displacing the motor

in the direction of the driving shaft and angularly re-adjusting the position of the motor to effect a re-alignment of the motor-drive-shaft and transmission-shaft.

6. The combination with a typewriting machine, having a platen-carriage, movable in letter-feed and return directions, a rack on the carriage, and a pinion meshing with the rack, of a motor having a drive-shaft, a transmission-shaft connected to the pinion and to the drive-shaft, and pivotal means for radially adjusting the position of the motor in the direction of the transmission shaft to effect displacement or alignment of the motor to the transmission-shaft.

7. The combination with a typewriting machine, having a platen-carriage, movable in letter-feed and return directions, a rack on the carriage, and a pinion meshing with the rack, of a motor having a drive-shaft, a transmission-shaft connected to the pinion and releasably connected to the drive-shaft, and pivotal means for displacing the motor to give access to certain other parts of the machine and then effect the re-alignment of the motor-drive-shaft and transmission-shaft.

8. The combination with a typewriting machine, having a platen-carriage, movable in letter-feed and return directions, a rack on the carriage, a pinion meshing with the rack, a drive-shaft for the pinion, and a clutch-member on the drive-shaft, of a transmission-gearing, a clutch-member on the transmission-gearing, and means for shifting the shaft which carries the pinion and one of the clutch-members into position to cause the clutch-members to engage one another.

9. The combination with a typewriting machine, having a platen-carriage, movable in letter-feed and return directions, a rack on the carriage, a pinion meshing with the rack, a drive-shaft for the pinion, and a clutch-member on the drive-shaft, of a transmission-gearing, a clutch-member on the transmission-gearing, and means for shifting the shaft which carries the pinion and one of the clutch-members into position to cause the clutch-members to engage one another without disengaging the pinion from the rack.

10. The combination with a typewriting machine, having a platen-carriage, movable in letter-feed and return directions, a rack on the carriage, a pinion meshing with the rack, and a drive-shaft for the pinion projecting rearward from the machine, and having a clutch-member thereon behind the machine, of a transmission-gearing comprising a clutch-member behind the machine, and means for shifting the shaft rearward and backward to make and break the driving connections by causing the clutch-members to engage and disengage each other.

11. The combination with a typewriting

- machine, having a platen-carriage, movable in letter-feed and return directions, a rack on the carriage, a pinion meshing with the rack, and a drive-shaft for the pinion projecting rearward from the machine, and having a clutch-member thereon behind the machine, of a transmission-gearing comprising a clutch-member behind the machine, means for shifting the shaft rearward and 5 projecting rearward from the machine, and having a clutch-member thereon behind the machine, of a transmission-gearing comprising a clutch-member behind the machine, means for shifting the shaft rearward and having a clutch-member thereon behind the machine, of a transmission-gearing comprising a clutch-member behind the machine, means for shifting the shaft rearward and 10 backward to make and break the driving connections by causing the clutch-members to engage and disengage each other, a motor for driving the transmission-gearing, and key-controlled means for concomitantly 15 closing the motor-circuit and effecting the engagement of the clutch-members with each other.
12. The combination with a typewriting machine, having a platen-carriage, movable in letter-feed and return directions, a rack on the carriage, a pinion meshing with the rack, and a drive-shaft for the pinion projecting rearward from the machine, and having a clutch-member thereon behind the machine, of a transmission-gearing comprising a clutch-member behind the machine, means for shifting the shaft rearward and 20 backward to make and break the driving connections by causing the clutch-members to engage and disengage each other, a motor for driving the transmission-gearing, and means automatically controlled by a margin-stop, on movement of the carriage, for concomitantly closing the motor-circuit and 25 effecting the engagement of the clutch-members with each other, for return movement of the carriage.
13. The combination with a typewriting machine, having a platen-carriage, movable in letter-feed and return directions, a rack on the carriage, a pinion meshing with the rack, and a drive-shaft for the pinion projecting rearward from the machine, and having a clutch-member thereon behind the machine, of a transmission-gearing comprising a clutch-member behind the machine, a motor for driving the transmission-gearing, means for concomitantly closing 30 the motor-circuit and thrusting the pinion-shaft with the clutch-member thereon rearward, to bring the clutch-members into engagement with each other, and means automatically controlled by a margin-stop for concomitantly breaking the motor-circuit and drawing forward the pinion-shaft with the clutch-member thereon for disengaging the clutch-members.
14. The combination with a typewriting machine, having a platen-carriage, movable in letter-feed and return directions, of a transmission-gear casing containing gearing for driving the carriage, said gearing comprising a pinion, a worm-gear set in a chamber in the casing, in mesh with the pinion, 35 a shaft for the worm, and a hub to which the pinion is keyed; the hub being journaled for rotation in one wall of the casing.
15. The combination with a typewriting machine, having a platen-carriage, movable in letter-feed and return directions, of a transmission-gear casing containing gearing for driving the carriage, said gearing comprising a pinion, a worm-gear set in a chamber in the casing, in mesh with the pinion, 40 a shaft for the worm, and a hub to which the pinion is keyed; the hub being journaled for rotation in one wall of the casing, and carrying one member of a clutch on the outer face thereof.
16. The combination with a typewriting machine, having a platen-carriage, movable in letter-feed and return directions, of a transmission-gear casing containing gearing for driving the carriage, means for holding the gear-casing in fixed position on the back 45 of the typewriting machine, a motor, supported independently of the typewriting machine, having a motor-shaft, and pivotal means for adjusting the position of the motor on its support, to align the shaft thereof with the shaft of one of the gears in the gear-casing; the motor being demountably secured to its support, and the gear-casing being demountably secured to the machine.
17. The combination in a typewriting machine, having a platen-carriage, movable in letter-feed and return directions, a rack on the carriage, a pinion meshing with the rack, a shaft for the pinion, projecting rearward therefrom, and having at its rear one member of a clutch, a bracket in which the shaft is journaled, and means for shifting the shaft, with the clutch-member thereon, rearward, comprising a rock-shaft, also journaled in said bracket, and having an arm 50 thereon for engagement with the first-mentioned shaft.
18. The combination with a typewriting machine, having a platen-carriage, movable in letter-feed and return directions, a rack on the carriage, a pinion meshing with the rack, and a shaft to which the pinion is made fast, and which projects rearward of the machine, one member of a clutch fast to the shaft near the rear thereof, of a gear-casing demountably secured at the rear of the machine, and containing gearing comprising a hub in which the end of the shaft is journaled, a clutch-member on the hub for engagement with the clutch-member on the shaft, a pinion on the hub, a worm meshing with the pinion on the hub, a shaft for the worm, and a motor having a shaft set in a hollow in the worm-shaft, substantially at right angles to the first-mentioned shaft; the gear-casing being demountably secured to the typewriting machine, and the motor being adjustable rearward on its support, whereby, with the motor-shaft and worm-shaft in engagement, the motor and the gear- 55

casing may be shifted rearward to disengage the first-mentioned shaft from the gear-casing, and whereby the gear-casing and the worm-shaft may then be moved laterally to disengage the worm-shaft from the motor-shaft.

19. The combination with a typewriting machine, having a platen-carriage, movable in letter-feed and return directions, a rack 10 on the carriage, a pinion meshing with the rack, and a shaft to which the pinion is made fast, and which projects rearward of the machine, one member of a clutch fast to the shaft near the rear thereof, of a gear-casing 15 demountably secured at the rear of the machine, and containing gearing comprising a hub in which the end of the shaft is journaled, a clutch-member on the hub for engagement with the clutch-member on the 20 shaft, a pinion on the hub, a worm meshing with the pinion on the hub, a shaft for the worm, and a motor having a shaft set in a hollow in the worm-shaft, substantially at right angles to the first-mentioned shaft; 25 the gear-casing being demountably secured to the typewriting machine, and the motor being pivotally mounted on its support, independently of the machine, for a rearward and forward swing, whereby, with the motor-shaft and worm-shaft in engagement, the 30 motor and the gear-casing may be shifted rearward to disengage the first-mentioned shaft from the gear-casing, and whereby the gear-casing and the worm-shaft may then 35 be moved laterally to disengage the worm-shaft from the motor-shaft.

20. The combination in a typewriting machine, having a platen-carriage, movable in letter-feed and return directions, a tabulator-stop frame extending longitudinally of the machine, at the rear thereof, tabulator-stops adjustable to selected column-positions along the tabulator-frame, and means for returning the carriage, comprising a rack on 40 the carriage, forward of the tabulator-stop frame, a pinion meshing with the rack, a shaft to which the pinion is made fast, and which projects rearward, under the tabulator-stop frame, a clutch-member on the 45 shaft, to the rear of the tabulator-stop frame, and means for shifting the shaft with the clutch-member rearward and forward, without bringing either the pinion or the clutch-member into the plane of the tabulator-stop frame, thereby permitting the column-stops to be shifted along the tabulator-stop frame from one to the other side of the 50 rearwardly-projecting shaft.

21. The combination with a typewriting machine having a platen-carriage movable in letter-feed and return directions, of a 60 motor having a drive shaft, a pivotal support for said motor, and transmission gearing mounted adjacent said motor, said 65 transmission gearing including a shaft re-

movably connectible to said motor drive shaft and operatively associable with said carriage, said motor and transmission gearing being tiltable as a unit about said pivotal support toward the plane of the base 70 of the machine to disconnect said transmission gearing from said carriage.

22. The combination with a typewriting machine having a platen-carriage movable in letter-feed and return directions, of a 75 motor having a drive shaft, a pivotal support for said motor, and transmission gearing mounted adjacent said motor, said transmission gearing including a shaft removably connectible to said motor drive shaft and operatively associable with said carriage, said motor and transmission gearing being tiltable as a unit about said pivotal support 80 toward the plane of the base of the machine to disconnect said transmission gearing from said carriage, and said transmission gearing and motor being separable from each other by relative withdrawal in the 85 direction of the longitudinal axis of said motor shaft.

23. The combination with a typewriting machine having a platen-carriage movable in letter-feed and return directions, of a motor having a drive shaft, a common support for said machine and said motor, a pivotal support for said motor above said common support, transmission gearing including a shaft removably connectible to said motor drive shaft, and a second shaft for driving said carriage, said carriage-driving shaft being operatively associable with said transmission shaft and having a portion extending within the frame of the machine, said motor and transmission gearing being 95 tiltable as a unit about the pivotal support toward said common support to disconnect said transmission gearing from said carriage-driving shaft.

24. The combination with a typewriting machine having a platen-carriage movable 100 in letter-feed and return directions, of a motor having a drive shaft, a common support for said machine and said motor, a pivotal support for said motor above said common support, transmission gearing including a shaft removably connectible to said motor drive shaft, and a second shaft for driving said carriage, said carriage-driving shaft being operatively associable with said transmission shaft and having a portion extending within the frame of the machine, said motor and transmission gearing being 105 tiltable as a unit about the pivotal support toward said common support to disconnect said transmission gearing from said carriage-driving shaft, and said transmission gearing being removable from said motor by withdrawal in the direction of the longitudinal axis of said motor drive shaft.

25. The combination with a typewriting 110

- machine having a platen-carriage movable in letter-feed and return directions, of a motor having a drive shaft, a pivotal support for said motor at the rear of the machine, the longitudinal axes of said carriage and said motor drive shaft being substantially parallel to each other, transmission gearing mountable on said machine and including a shaft removably connectible to said motor drive shaft, and a carriage-driving shaft operatively associate with said transmission shaft, said carriage-driving shaft having its major portion extending within the machine frame in a direction substantially at right angles to said motor drive shaft and said carriage, said motor and transmission gearing being tilttable as a unit about the pivotal motor support to connect and disconnect said transmission gearing and said carriage-driving shaft.
26. The combination with a typewriting machine having a platen-carriage movable in letter-feed and return directions, of a motor having a drive shaft, a pivotal support for said motor at the rear of the machine, the longitudinal axes of said carriage and said motor drive shaft being substantially parallel to each other, transmission gearing mountable on said machine and including a shaft removably connectible to said motor drive shaft, and a carriage-driving shaft operatively associate with said transmission shaft, said carriage-driving shaft having its major portion extending within the machine frame in a direction substantially at right angles to said motor drive shaft and said carriage, said motor and transmission gearing being tilttable as a unit about the pivotal motor support to connect and disconnect said transmission gearing and said carriage-driving shaft.
27. The combination with a typewriting machine having a platen-carriage movable in letter-feed and return directions, of a motor having a drive shaft, a pivotal support for said motor at the rear of the machine, the longitudinal axes of said carriage and said motor drive shaft being substantially parallel to each other, transmission gearing mountable on said machine and including a shaft removably connectible to said motor drive shaft, and a carriage-driving shaft operatively associate with said transmission
- shaft, said carriage-driving shaft having its major portion extending within the machine frame in a direction substantially at right angles to said motor drive shaft and said carriage, said motor and transmission gearing being tilttable as a unit about the pivotal motor support to connect and disconnect said transmission gearing and said carriage-driving shaft, and said motor being tilttable on its pivotal support independently of said transmission gearing to permit alignment of said motor shaft and said transmission shaft.
28. The combination with a typewriting machine having a platen-carriage movable in letter-feed and return directions, of transmission gearing for driving said carriage, said transmission gearing including a clutch-member, and an intermediate shaft operatively connected to said carriage and having a clutch-member, said shaft being shiftable to alternately connect and disconnect said clutch-members to make and break the driving connection without breaking the operative connection between said shaft and said carriage.
29. The combination with a typewriting machine having a platen-carriage movable in letter-feed and return directions, of transmission gearing including a casing block, a gear in said block, said gear having a hub which is operatively connectible to said platen-carriage, and a bearing for said hub, said bearing including a pair of separable bushings housed as a unit within said block and having oppositely inclined inner edges jointly forming a ball-race, and a plurality of ball-bearings in said race for centering said hub relatively to the block.
30. The combination with a typewriting machine having a platen-carriage movable in letter-feed and return directions, of transmission gearing including a casing block, a gear in said block, said gear having a hub which is operatively connectible to said platen-carriage, a bearing for said hub, said bearing including a pair of separable substantially disk-shaped bushings housed as a unit within said block and disposed to center said hub relatively to the block, said hub having a peripheral groove and said bushings having oppositely inclined inner edges co-operative with said peripheral groove to provided a ball-race, a plurality of ball-bearings in said ball-race, and means for assembling the ball-bearings and then securing said bushings within the housing of said casing block.

HENRY L. PITMAN.
